UNITED STATES PATENT OFFICE.

JULES REGOUT, JR., OF MAASTRICHT, NETHERLANDS.

MACHINE FOR RAISING NAP ON FABRICS.

1,217,129.

Specification of Letters Patent. Patented Feb. 20, 1917.

Application filed April 24, 1915. Serial No. 23,632.

To all whom it may concern:

Be it known that I, JULES REGOUT, Jr., manufacturer, a subject of the Queen of the Netherlands, residing at No. 18 Kleine 5 Lovierstraat, Maastricht, in the Kingdom of the Netherlands, have invented certain new and useful Improvements in Machines for Raising Nap on Fabrics; and I do hereby declare the following to be a full, clear, 10 and exact description of the invention, such as will enable others skilled in the art to which it appertains to make and use the same.

This invention relates to machines for 15 raising nap on fabrics and has for its primary object to provide a construction in which the raising action may be effected simultaneously in the direction of the warp of the fabric as well as transversely of the 20 same, whereby an even and highly efficient raising action is obtained.

Other objects of the invention are to provide a machine of this character in which the fabric is conducted over two different 25 groups of raising rollers which are rotatably mounted, partly in the direction of the warp and partly in that of the weft of the fabric, in a traveling carriage movable to and fro transversely to the traverse of 30 the fabric, and the raising rollers of one of which groups are adjustable in vertical direction for the purpose of controlling the raising action.

With these and other ends in view my invention consists in the arrangement, construction and combination of parts to be herein described and particularly pointed out in the appended claims.

In the drawings:—

40 Figure 1 is a plan view of a machine constructed in accordance with the present invention, some parts of the guiding rollers for the fabric being broken off for the sake of clearness;

45 Fig. 2 is a front elevation of the machine;

Fig. 3 is a side elevation of the same; and

50 Fig. 4 is a detail view, illustrating an adjustable bearing for one of the raising rollers.

Referring now to the drawings, in which similar numerals of reference indicate corresponding parts, 5 designates a carriage which is movable on rails 6 and which by 55 means of rods 7 and 8 is connected to the cranks 9 of a shaft 10 driven from any suit-

able power source. When this shaft is rotated it imparts a to and fro motion to the carriage 5. Transversely of this carriage, shafts 11 to 18 are mounted on the same 60 which are situated parallelly to each other and in the same horizontal plane. The shafts 11 to 18 have securely placed thereon the raising rollers 19 and are rotatably mounted in bearings 20 of the carriage 5. 65 As is to be seen from the drawings, two raising rollers 19 are mounted on each of the transverse shafts. The shafts 11 to 18 are arranged so closely to one another that the raising rollers of two adjacent shafts can- 70 not be arranged oppositely to one another; on the contrary, the rollers are arranged in staggered relation so that the rollers of one shaft always face free parts of the adjacent shaft. These rollers 19 execute a rais- 75 ing action in the direction of the weft threads of the fabric.

The raising rollers 19 fastened to the shafts 11 to 18 form four rows on lines transverse to the direction of the axes of 80 their shafts. Between these rows spaces 21, 22, 23 are left which serve for the reception of another group of raising rollers, indicated by the numerals 24, 25, 26. These rollers are mounted in bearings 27 fastened 85 to the carriage frame and serve to effect a raising action on the fabric in the direction of its warp threads.

The raising rollers 24, 25, 26 are vertically 90 adjustable in height. For this purpose the bearings 27 for the rollers are so constructed as to possess an adjustability in vertical direction. Referring particularly to Fig. 4, the bearings 27 consist of an upper part 28 comprising the brasses and cap-piece, and a 95 lower part 29 forming a base fixed to the carriage frame. Both parts are connected with one another by means of a screw bolt 30, which in one part is provided with right handed thread and in the other part with 100 left handed thread. The upper part 28 is provided with recesses 31 by which it is guided on corresponding extensions 32 formed on the base 29. By rotating the 105 screw bolts 30 in one direction the upper parts of the bearings together with the rollers mounted therein are raised and by rotating the bolts in the opposite direction the rollers are lowered. The rotation of the screw bolts may be effected by means of a 110 rod, by inserting the same into recesses 33 formed in the screw bolts.

The raising rollers of both groups usually form one common horizontal contact surface for the fabric to be raised. Due to the adjustability of one roller group with respect to the other the raising action can be easily controlled at will. If the rollers 24, 25, 26 are so adjusted as to raise above the upper contact surface formed by the rollers 19 the raising action will be more efficient in 5 the direction of the warp threads of the fabric, while if the afore-mentioned rollers are lowered so far as to be under the upper surface of the rollers 19, these latter will execute a more effective raising action on 10 the fabric in the direction of its weft threads. Besides, the rollers 24, 25, 26 can be lowered so far that they will no longer come into contact with the fabric on which 15 the nap is to be raised, thus remaining in a 20 non-operative position.

Underneath the raising rollers two electric motors 34 and 35 are fastened to the frame of the carriage 5, which serve to drive the rollers.

25 Motor 34 imparts rotation to the shaft 11 through the medium of an open belt 36 and motor 35 imparts rotation to the shaft 16 through the medium of an open belt 37 too. 30 The driving shafts of the motors 34 and 35 revolve in opposite directions. From the shafts 11 and 16 rotation is transmitted to the remaining shafts 12, 13, 14, 15, 17 and 18 by means of open and crossed belts, as 35 shown, in such a manner that each two rollers which are situated one opposite to the other always rotate in opposite directions.

Mounted in brackets 41 at the front and 40 the rear end of the carriage frame 5 are shafts 38 and 39, respectively. Shaft 38 is rotated by the motor 34 and shaft 39 by motor 35 through the medium of open belts 40.

45 The shaft 38 transmits its rotation to the longitudinal raising roller 25 by means of a half crossed belt 42, and in similar manner shaft 39 transmits the rotation imparted thereto to the longitudinal raising rollers 50 24 and 26 by means of two half crossed belts 43. According to this arrangement, roller 25 will rotate in a direction opposite to that of the rollers 24 and 26.

Pairs of rollers 45, 46 are mounted in the 55 upper ends of standards 44 and serve to guide the fabric 47 through the machine in the direction of the axes of the raising rollers 19 and transversely to the rollers 24, 25 and 26. The guiding rollers 45, 46 are 60 adjustable in height and for this purpose their bearings 48 are slidably mounted in any well-known manner in the upper ends of the standards 44. Thereby it is allowed to bring the fabric into contact with the 65 raising rollers or to hold it free from the

same. The fabric is further guided by means of guiding rollers 49 rotatably mounted in standards 50.

As to the guiding of the fabric I do not wish to be limited to the mechanism illustrated on the drawings, the fabric may also be guided in any other suitable manner; besides the rollers 45, 46 arranged at two sides of the machine, a plurality of guiding rollers may be provided between the 75 same.

It is obvious that various modifications may be made in the construction shown and above particularly described within the principle and scope of my invention.

What I claim as new and desire to secure by Letters Patent, is:—

1. A machine for raising nap on fabrics, comprising means for guiding the fabric to be operated on through the machine, a traveling carriage, means for imparting a to and fro motion to this carriage, a plurality of raising rollers mounted in the carriage, motors attached to the carriage frame for rotating the raising rollers, these rollers being arranged partly in the direction of the traverse of the fabric and partly transversely of the traverse, and one set of rollers being adjustable in height with relation to the other rollers.

2. A machine for raising nap on fabrics, comprising means for guiding the fabric to be operated on through the machine, a traveling carriage, a power driven crank shaft connected to the carriage by suitable rods and imparting a to and fro motion to the carriage transversely of the traverse of the fabric, a plurality of raising rollers mounted in bearings fastened to the carriage, motors attached to the carriage frame for rotating the raising rollers, these rollers forming two different groups, the rollers of one of these groups being arranged in the direction of the traverse of the fabric and the rollers of the other group transversely thereof, the bearings for the latter rollers being adjustable in height so as to allow these rollers to be raised and lowered with relation to the other rollers.

3. A machine for raising nap on fabrics, comprising guiding rollers for the fabric rotatably mounted in suitable standards at two sides of the machine and partly adjustable in height, a traveling carriage being movable to and fro transversely of the 120 traverse of the fabric, a plurality of raising rollers rotatably mounted in bearings fastened to the carriage, motors attached to the carriage for driving the raising rollers, these rollers forming two groups, the 125 rollers of one group being arranged in staggered relation to one another and having their axes in the direction of the traverse of the fabric and the rollers of the other group being arranged transversely thereof 130

in the spaces left between the several rows formed by the former rollers, and the rollers lying transversely of the traverse of the fabric being journaled in bearings adjustable in height, so as to allow these rollers to be raised and lowered with relation to the other rollers.

4. A machine for raising nap on fabrics, comprising guiding rollers for passing the fabric through the machine, a traveling carriage being movable to and fro transversely of the traverse of the fabric, a plurality of raising rollers mounted in bearings fastened to the carriage and forming two groups, the 15 raising rollers of one of these groups being arranged in the direction of the traverse of the fabric and the rollers of the other group being arranged transversely thereof, the bearings for the raising rollers of said lat-

ter group consisting of two parts, the upper 20 part comprising the brasses and cap-piece and being guided in vertical direction on extensions of the lower part forming the base, both parts being connected with one another by means of a screw bolt, provided 25 at its ends with right handed and left handed thread respectively so as to cause the upper part of the bearing to be raised or lowered together with the raising roller journaled therein, when rotated in one direction or the other.

In testimony whereof I have signed my name to this specification in the presence of two subscribing witnesses.
